POLE FEEDING DEVICE FOR POLE PEELING MACHINES

Filed Jan. 9, 1948

UNITED STATES PATENT OFFICE

2,505,168

POLE FEEDING DEVICE FOR POLE
PEELING MACHINES

Ray C. Augustin, Sedalia, Colo.

Application January 9, 1948, Serial No. 1,395

2 Claims. (Cl. 144—246)

2

1 This invention relates to a pole peeling machine of the type commonly known as rossing machines for decorticating timber for the production of poles, such as telephone, telegraph, electric, and fence poles from logs. The principal object of this invention is to provide a pole feeding device for pole peeling machines whereby the operator will have instant and accurate control over the travel of the pole through the peeling machine, in order to obtain the most complete and efficient peeling action thereon.

A further object is to provide a device of this character which will be of small size, lightweight, and self-contained, so that it may be readily moved from job to job.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a plan view of the improved pole peeling machine; and

Fig. 2 is a side view thereof.

The mechanism for the improved machine is carried on a rectangular main frame consisting of horizontal members 10 and 11 supported on vertical posts 12. Two V-shaped side frames, each consisting of two inclined members 13 and 14 positioned at an angle of 90° to each other, are positioned at each side of one extremity of the main frame.

Each of the inclined members 13 and 14 carries two roller studs 15. A rotatable ring plate 16 is mounted between the four rollers 15 of the members 13, and a similar rotatable ring plate 17 is mounted between the four rollers 15 of the members 14. The edges of the plates 16 and 17 ride in grooves in the rollers 15 so as to be firmly supported, yet freely rotatable therein.

The peripheral edges of both plates 16 and 17 are grooved to receive an endless cable 18 which extends around one-half the circumference of each plate and around idler pulleys 19 positioned at each side of the frames 14 between the plates. Thus, it can be seen that if either plate 16 or 17 is rotated, the other plate will be simultaneously rotated in the same direction.

The ring plate 17 is manually rotated in either direction by means of a projecting arm 24 which

is connected by means of a connecting rod 25 with a hand lever 26. The connections between the arm 24 and the lever 26 are made by universal joints, preferably ball-and-socket joints 27.

5 5 The lever 26 is mounted in a hinge clip 28 secured on a cross shaft 29. The axis of the hinge clip is at right angles to the axis of the shaft 29, so that the lever 26 may be swung in a plane parallel to the axis of the shaft 29 for the purpose of imparting rotation to the ring plate 17.

The plates 16 and 17 carry oppositely positioned shaft bearings 20 in which wheel axle shafts 21 are mounted, which extend diametrically across the plates. The shafts 21 carry 10 pneumatically tired wheels 22 upon which the pole to be peeled, indicated at 23, is carried.

The actual cutting or peeling is done by means of a rotary planer knife head 30 which is rotatably mounted in a knife frame 31. The knife frame is supported from a rotatable outer sleeve 32 which is rotatably mounted on the extremity of a cylindrical hinged boom 33. The boom 33 is welded or otherwise secured to, and projects perpendicularly from, a cross shaft 34 mounted in bearing hangers 35 on one extremity of the top frame 11.

The boom 33 carries a motor platform 36 upon which a suitable drive motor 37 is mounted. The motor is positioned with relation to the axis of the shaft 34 to substantially counterbalance the weight of the boom 33 and the frame 31. The cutter head 30 is driven from the motor 37 by means of an endless belt 38.

The boom is raised and lowered from a lifting arm 39 which is secured on, and projects from, the shaft 29 through the medium of a connecting link 51. Thus, it can be seen that if the hand lever 26 is swung longitudinally of the frame 11, it will raise and lower the cutter head 40 30. If this lever is swung laterally of the longitudinal axis of the frame, it will rotate the ring plates 16 and 17. Simultaneous movements of both the cutter head and the ring plates can be obtained by movements in intermediate directions.

45 The wheels 21 and 22 are driven from a second motor 40 and a speed reducer 41 through the medium of endless belts 42 and 43. The belt 42 drives a first countershaft 44, and the belt 43 drives a second countershaft 45 through the medium of suitable belt pulleys.

The shaft 44 carries a pair of belt pulleys, from which a pair of belts 47 extend to belt pulleys on the shaft 21 at each side of the wheel 22 on the ring plate 17. The second countershaft 45 is also

provided with a pair of belt pulleys from which a pair of endless belts 46 extends to belt pulleys on each side of the wheel 22 on the ring plate 16.

The wheels in Fig. 2 rotate in a counter-clockwise direction so as to rotate the pole 23 in a clockwise direction. The cutter head 30 also rotates in a clockwise direction so that the movements of the pole and the cutter head are opposed for quickly peeling the pole.

The poles are fed to the machine in any desired manner, usually from a truck or dolly which supports one end of the pole while the other rests on the wheels 22. The operator can cause the pole to travel forward and back at any desired speed by inclining the wheels 22 at various angles and in alternating directions by means of the hand lever 26. He can also lower the cutter head into cutting position and hold it against the pole by this same handle.

Since the knife frame is mounted on the sleeve 32, and since the latter is rotatable on the boom 33, the cutter head can tilt to accommodate the natural taper of the pole, if any. If it is desired to prevent the cutter head from tilting, a latch 48 is provided on the boom. The latch has one side rounded and the other straight. It is rotatable on the boom so that the rounded side may be brought between two pins 49 on the sleeve 32 to prevent the latter from rotating, or the latch may be rotated 180° to bring the flat side toward the sleeve 32 out of contact with the pins 49.

The knife frame 31 is supported in proper spaced relation to the pole by means of suitable runners 50 which are vertically adjustable in any desired manner to adjust the depth of cut of the knives.

While a specific form of the improvement has been described and illustrated herein, it is desired to be understood that the same may be varied, within the scope of the appended claims, without departing from the invention.

Having thus described the invention, what is claimed and desired secured by Letters Patent is:

1. In a pole peeling machine, a pole feeding device comprising: an elongated frame; a pair of

inclined supporting members carried by said frame below a cutter head and forming a V-shaped frame; an annular, rotatable disc mounted on each supporting member in V-shaped relation; a wheel axle extending across each disc; a wheel mounted on each axle, said wheels being in opposed relation so as to support a pole therebetween; an endless flexible member passing about both discs to cause them to rotate in unison; means for rotating said discs to vary the angle of said wheels in relation to the axis of said pole; and means for rotating said wheels.

2. In a pole peeling machine, a pole feeding device comprising: an elongated frame; a pair of inclined supporting members carried by said frame below a cutter head and forming a V-shaped frame; an annular, rotatable disc mounted on each supporting member in V-shaped relation; a wheel axle extending across each disc; a wheel mounted on each axle, said wheels being in opposed relation so as to support a pole therebetween; an endless flexible member passing about both discs to cause them to rotate in unison; an arm projecting from one disc; a manual operating lever; a connecting rod extending from said arm to said lever for rotating said discs to vary the angle of said wheels in relation to the axis of said pole; and means for rotating said wheels.

RAY C. AUGUSTIN.
